United States Patent

Des. 237,574
Patented Nov. 11, 1975

237,574

TUMBLER

Frank Goertzen, 1 Oriole Road, Toronto M4V 2E7,
Ontario, Canada

Filed Mar. 28, 1974, Ser. No. 455,940

Term of patent 14 years

Int. Cl. D7—01

U.S. Cl. D7—6

FIG. 1

FIG. 2

FIG. 3

FIG. 4

FIG. 5

FIG. 1 is a side perspective view of a tumbler showing my new design;

FIG. 2 is a top plan view of FIG. 1;

FIG. 3 is a front elevation view taken along the line 3—3 of FIG. 2;

FIG. 4 is a cross sectional view taken along the line 4—4 of FIG. 2;

FIG. 5 is a bottom plan view of FIG. 3.

I claim:

The ornamental design for a tumbler substantially as shown and described.
